TEXTILE MACHINES

John K. P. Mackie, Belfast, Northern Ireland, assignor to James Mackie & Sons, Limited, Belfast, Northern Ireland

Filed June 26, 1962, Ser. No. 205,383

Claims priority, application Great Britain June 29, 1961
5 Claims. (Cl. 57—58.59)

This invention relates to the spinning of yarn from sliver.

For the twisting or plying of yarns there are sometimes used machines of the so-called two-for-one inflow type in which the material to be twisted is taken from a stationary supply package and is caused to be ballooned by a flyer and delivered to a package within the balloon on which it is wound. For each rotation of the flyer, two turns of twist are put into the yarn, one on the feed side of the flyer and the other on the delivery side.

Such a machine does not suggest itself as a satisfactory machine for converting sliver into yarn. The distance from the drafting head which delivers the sliver to the eye of the flyer is necessarily rather long and sliver is very weak in tension. On the feed side of the flyer only half the full amount of twist is put into the sliver and, consequently there is only a small strengthening of the sliver until it has passed beyond the flyer and the frequency of breakages is high.

The invention is concerned with improving the machine in that respect.

In accordance with the invention, the whole of the twist is put into the sliver on the feed side of the flyer with a consequent strengthening of the sliver and reduction in the frequency of breakages. This is effected by the provision in the sliver path of a false twist tube which is carried round with the flyer and is rotated about its own axis in the direction required to allow the twist which is put in on the delivery side of the flyer to run back past the tube into the material on the feed side of the flyer.

Preferably, the false tube is carried by the flyer and is set thereon with its axis vertical. Means have to be provided for rotating it about its axis and these can be means provided essentially for another purpose. Its disposition should be such that there are no abrupt changes of direction in the sliver path leading to it which would prevent the twist from running freely back into the balloon.

The spindle on which the yarn is wound can be driven independently of the flyer as in the case of twisting machine with which our copending patent application Serial No. 205,384, filed June 26, 1962, is concerned. The yarn speed is determined by the speeds of the delivery rollers of the drafting head. The degree of twist of the finally produced yarn is dependent on the ratio of the yarn speed and the flyer speed which are variable independently of each other.

An example of a machine in accordance with the invention will now be described with reference to the accompanying drawing in which:

FIGURE 1 shows, somewhat diagrammatically, a single spindle of the machine; and

FIGURE 2 is a section plan taken on the line A—A in FIGURE 1, showing the drive for the false twist tube.

FIGURE 1 shows sliver 2 being delivered to a spindle 4 of the machine and after being twisted into yarn. The sliver which has passed through a drafting head 6 having delivery rollers 8 passes through a stationary guide eye 10 attached to the machine framework to and through a false twist tube 12 which forms the eye of a rotary flyer 14. Thence, the sliver passes up through a stationary tube 16 arranged coaxially with the flyer to a pair of driven take-up rollers 18 providing a yielding nip so that they act merely to tension the yarn. The

2

yarn is then laid on a package 20 carried by the spindle 4, by a butterfly yarn guide 22 which is reciprocated by a traverse scroll 24.

The flyer which is in the form of a disc, is rotated about a vertical axis by a drive including an internally toothed belt 26 positively engaging a toothed pulley 28 on the flyer shaft 30. Rotation of the flyer causes the length of sliver between the false twist tube 12 and the stationary eye 10 to billow into a balloon at 32 which is whirled around the spindle 4, the take-up roller 18 and the tube 16, between inner and outer balloon guide rings 34 and 36.

For each revolution of the flyer, two turns of twist are given to the sliver, one turn, were it not for the false twist tube, being inserted between the delivery rollers 8 and the eye 10 and the other between the flyer and the take-up rollers 18 within the balloon. The length of the sliver from the delivery rollers 8 to the flyer is necessarily long and if only one turn of twist is put into the sliver on its way to the flyer for each revolution of the flyer frequent breakages are liable to occur. To avoid this, the false twist tube is rotated in the same direction as the flyer so as to cause the twist inserted on the delivery side of the flyer between it and the stationary tube 16 to run past the twist tube 12 and add itself to the twist put in on the feed side of the flyer. The sliver is thus considerably strengthened where strength is most necessary. Provided that there are no surfaces against which the sliver is strongly pressed as occurs at an abrupt change in the direction of the sliver path, the twist can run back as far as the delivery rollers 8. The amount of twist put into the sliver depends on the flyer speed and on the linear speed of the sliver through the machine which is determined by the delivery rollers 8.

The take-up rollers 18 and spindle 4 are driven independently of the flyer by a toothed belt 42 which drives a pulley 44 rotatably mounted on the flyer spindle and integral with one, 46, of a pair of equal diameter sun wheels 46, 48 the other one, 48, of which is carried by the tube 16 on the other side of the flyer and within the balloon. The sun wheels are connected together through a pair of coaxial planet wheels 50, 52 of equal diameter and mounted one on each side of the flyer on a spindle 54 passing through and carried by the flyer. Each sun wheel is connected to the adjacent planet wheel by one of a pair of integrally toothed belts 56, 58. Thus, rotation of the sun wheel 46 by its pulley 44 causes an equal rotation of the other sun wheel 48 within the balloon irrespective of the speed rotation of the flyer.

The sun wheel 48 is integral with a gear wheel 60 which drives a spindle driving shaft 62 off-set from the axis of rotation of the flyer. The shaft 62 is provided between its ends with a spiral gear 64 meshing with a similar gear in driving connection with one of the take up rollers 18. The other roller is lightly loaded so that only a yielding nip is provided and the rollers do no more than tension the yarn in the balloon.

The upper end of the spindle driving shaft 62 is also provided with a spiral gear 66 meshing with a corresponding gear 68 on the traverse scroll 24 so that the traverse scroll is driven directly by the spindle driving shaft. Rotation of the scroll causes the butterfly yarn guide 22, which engages in the traversing groove 70 of the scroll, to be reciprocated parallel to the axis of the spindle so that the yarn is laid evenly onto the package carried by the spindle. The spindle is driven from the shaft through the scroll to which it is connected by a chain drive 72 through a slipping clutch 74.

The gearing between the spindle and the take-up rollers is arranged so that the take-up speed of the pack-

age, with no clutch slippage, always exceeds the let-off speed of the delivery rollers of the drafting head. In use, therefore, the clutch is continuously slipping so that the spindle is driven at the correct speed to take up the yarn delivered to it. The pressure on the clutch 5 determines the tension of the yarn between the rollers 18 and the package and this pressure is adjustable so that a correct yarn tension can be obtained for any yarn specification.

The spindle 4, traverse scroll 24, take-up rollers 18 10 and tube 16 together with the drive for the take up rollers and spindle, are carried by a common bracket diagrammatically shown at 76 within the balloon. This bracket is mounted on the tube 16 which in turn is mounted in bearings on a projection 78 extending from 15 the upper side of the flyer. Means have to be provided to hold or immobilize the tube 16 and hence the bracket 76 against rotation with the flyer. This is done by positively connecting a toothed sun wheel 80 fixed to the tube 16 within the balloon to a stationary fixed co-axial 20 toothed sun wheel 82 of the same diameter surrounding the flyer shaft outside the balloon, through a pair of equal coaxial toothed planet wheels 84, 86 mounted one on each side of the flyer on a common spindle passing through and carried by the flyer. The sun wheels are 25 connected to the adjacent planet wheels by means of internally toothed bolts 88. As the sun wheel 82 outside the balloon is fixed in a stationary position and as the sun wheel within the balloon is of the same diameter and as the two planet wheels are of the same diameter, the sun wheel 80 within the balloon is held stationary 30 when the flyer rotates.

The false twist tube 12 through which the sliver passes is mounted on a bracket 90 carried by the flyer and is 35 rotated through a pulley 92 on it which engages and is frictionally driven by the back of the belt 88 (see FIGURE 2). The tube is thus rotated in the same direction as the flyer. The twist inserted in the delivery side of the flyer is, therefore, free to run back and adds itself to the twist which is put into the sliver in the balloon.

The speed and/or design of the false twist tube is such that at least the twist on the delivery side of the flyer is inserted in the balloon on the feed side, but in practice it may be desirable to use the tube to insert a turn or turns of false twist on the balloon further to strengthen the yarn. This false twist will disappear as 40

4
the yarn passes through the tube and will not be present on the delivery side.

It is not essential to provide separate independent drives for the take-up rollers and the flyer as shown in the drawings. The speed of the yarn through the machine can be varied by varying the speed of the delivery rollers of the drafting head as therefore can the degree of twist imparted to the sliver. Consequently, a more simple form of drive can be adopted in which the take-up rollers are driven through the flyer.

I claim:

1. A spinning machine of the two-for-one inflow type having a rotatable flyer to balloon sliver around a package support, a bracket plate on which said package support is carried and which is rotatably mounted on an axial extension of the flyer, a false twist tube mounted on the flyer in the sliver path, and means to rotate the false twist tube about its own axis in the direction required to allow the twist, which is put into the sliver on the delivery side of the flyer, to run back past the said false twist tube into the sliver on the feed side of the flyer.

2. A spinning machine as claimed in claim 1 in which the false twist tube is carried by the flyer with its axis vertical and arranged so that there are no abrupt changes in the sliver path leading to it the tube being rotated in the same direction as the flyer.

3. A spinning machine as claimed in claim 1 in which the means to drive the false twist tube comprises a toothed belt extending between a planet wheel carried by the flyer, and a sun wheel fixed to the bracket within the balloon.

4. A spinning machine as claimed in claim 3 in which the outer surface of the toothed belt frictionally engages a pulley connected to the false twist tube.

5. A spinning machine as claimed in claim 1, in which the bracket plate is held stationary despite the rotation of the flyer by the said means employed to rotate the false twist tube.
